PICKUP, DISPENSING, AND LOADING MARKERS FOR GAMES

Charles C. Winters, R.D. 6, Butler, Pa.
Filed Mar. 14, 1960, Ser. No. 14,756
10 Claims. (Cl. 221—175)

This invention relates generally to apparatus for picking up, dispensing and loading markers for games and more particularly for use with washer type markers on rod type carriers.

In playing games where it is necessary to place markers on a card or on the playing surface of a game, it is difficult to hold extra markers in the hands and accurately place one marker at a time while still retaining additional markers in the hands. One is apt to drop one or more of the additional markers on the card or playing surface and either disturb or forget which are the proper markers as games of this character move very fast and one does not have time to ponder but must act or move fast. Thus the mistaken or improperly deposited marker on the card or playing surface may lead to inaccuracies ruling out the player. This sometimes also proves to be embarrassing to the player making the mistake and at the same time provokes the other players. Such conditions can readily be avoided by the dispensing member comprising the improvement of one portion of this invention wherein a rod or pencil, having a spring at both ends, is employed to hold washer type markers and to pick up or dispense them when held vertically. The washer holding spring at the pickup end is very close to one end of the rod permitting the spring to quickly pick up a washer and move it onto the rod. The washer holding spring at the other or dispensing end of the rod is spaced a washer thickness from the rod end to permit only one washer to be dispensed for each application of pressure on the washers toward the dispensing end of the rod.

Another phase in this problem is in quickly loading these rods. Although a few washers may be quickly picked up on the pick up end of the rod, these rods may be quickly loaded when employed with a loading box and tube. This quickly aligns many washers that permits the rod to be inserted therein.

The loading box and tube also function as a carrier for a supply of the washer markers and rods.

Other objects and advantages appear hereinafter in the following description and claims.

The accompanying drawings show for the purpose of exemplification without limiting the invention or claims thereto, certain practical embodiments illustrating the principles of this invention wherein:

FIG. 1 is an enlarged view partly in section and with parts broken away illustrating the rod comprising this invention.

FIG. 2 is a perspective view showing the loading box with the loading tube stored therein.

FIG. 3 is a perspective view of the loading tube.

FIG. 4 is a sectional view of the loading box and the loading tube.

FIG. 5 is a perspective view of the loading box and the loading tube in operative cooperation.

FIG. 6 is a plan view of the loading box and loading tube with a rod projected thereinto.

Referring particularly to FIG. 1 of the drawings the rod 1 is preferably round and made of material such as plastic but of course may be made of any suitable material in which the slots 2 and 3 may be formed or otherwise cut therein which slots slope inwardly to or beyond the center of the rod as they approach the ends of the rod. At the inner end of the slot 2 a hole 4 is drilled transversely through the rod. At the inner end of the slot 3 a hole 5 is drilled transversely through the rod.

2

However, the hole 4 is closer to the end 6 of the rod than is the hole 5 to the end 7 of the rod.

In each of the slots 2 and 3 is a spring member 8 having a bend or shoulder 9 with a short end section 10 adjacent thereto, whereas the other end of the spring 8 is provided with a long end section 11. The whole of the springs 8 in each instance is the same and it lies in a single plane. The fact that the hole 4 is closer to the end 6 places the shoulder 9 of the spring 8 close to the curved end 6. The end 7 of the rod being further from the shoulder 9 provides for the extension 12 on the rod which is substantially the same length as the thickness of the washer 13. Thus if the end 6 of the rod is pushed into the bore 14 of the washer 13, the shoulder 9 will spring inwardly and allow the washer 13 to pass thereover and be held on the rod 1 by the inner shoulder 15 of the shoulder 9 on the spring 8. If the washers 13 are stacked on the rod 1 and pressure is applied on the washers toward the end 7 which is on a table or card surface one washer 13 will be permitted to be pushed over the shoulder 9 of its spring and rest in the position as shown in FIG. 1. Further pressure will not feed the second washer on top of the first washer that is beyond the shoulder. Upon raising the rod the lowermost washer which is on the section 12 of the rod will be left in the proper position and thus dispensed from the end of the rod.

If the rod is turned upside down to simulate the position as shown at the top of FIG. 1, then downward pressure on the rod will cause the washer to again flex the spring inwardly and admit the washer onto the rod. Thus the rod dispenses the washers at one end and picks them up at the other end. The surface of the rod may carry characters as indicated at 29 which represents advertising matter to increase the friction between the rod and the washer marker when held for dispensing.

The box 16 as shown in FIGS. 2 and 4 to 6 is also preferably made of plastic material that is transparent. This box is provided with the end box means 17 and 18 and the front side 19 and the rear side 20 with a lid 21 hinged to the box as indicated at 22.

The rear wall 20 of the box extends downwardly to form the upwardly open cylindrical slot 23 which ends in the box bottom 24 to provide a semi-cylindrical slot 25 for the full length of the box. The box ends 17 and 18 extend to the tangent of the cylindrical surface 23 so as to provide a flat rest for the box.

As shown in FIGS. 2 to 6 a loading tube 26 is inserted through an opening in the end 17 of the box. This opening is defined by the short outwardly extending tube 27 that is of the same cylindrical size as the portion 23 and thus provides an exterior throat for the semi-cylindrical slot 25 outside of the box. The bore 28 of the tube 26 is of proper size to admit the loading tube 26 which is also tubular and is partially closed by the ring type flange 30 at one end which has an opening 31 in the axial center thereof with appropriate clearance slots 32 for the purpose of admitting the rod 1 and with the slots 32 passing the shoulders 9 on the springs 8. However, the hole 31 is not sufficiently large to pass the washers 13.

As shown in FIG. 2 the tube 26 with its flange 30 adjacent the bore 28 when placed in the box and when the lid thereof is closed prevents any washers from escaping the box and a series of loaded rods or loose rods and loose washers may thus be safely carried in the box without fear of loss when the latch 33 secures the lid in its locked position.

When it is desired to load the rods the loading tube 26 is positioned as illustrated in FIG. 5 and is rotated and reciprocated back and forth by hand causing the loose washers to align themselves and enter the open end of the tube 26 in proper alignment. When the tube is filled

there are usually additional aligned washers 13 in the upwardly open semi-cylindrical trough 25 even though the end of the tube 26 is spaced from the end of the box by reason of the flange 30 engaging the outer end of the tube 27 as shown in FIG. 6. With the washers all properly aligned in the tube 26 the rod 1 may be inserted through the plug washer 30 with the shoulder 9 of the spring 8 aligned with one of the slots 32 and forced upwardly through all of the aligned washers until it is completely filled. The loading tube 26 may then be withdrawn from the box and the loaded pencil or rod slid through the open end of the loading tube 26 ready for use.

I claim:

1. A hand dispenser for receiving and discharging washer markers of uniform thickness on a planar surface comprising a rod having a diameter that permits the washer markers to readily slide thereover, a longitudinally disposed slot in the side of the rod and adjacent each end of the rod, a spring in each slot having an anchor on one end and a shoulder on the other end connected by a stem, the anchor of each spring holding the same in the slot below the surface of the rod with the stem rising up in the slot to the shoulder that protrudes out of the slot for a distance greater than the clearance between the washer marker and the rod, the shoulder of each spring being rounded to permit a washer to depress the same into its slot when a washer marker is forcibly moved over the shoulder in either direction, one end of said rod extending from the shoulder of its spring a distance substantially equal to the thickness of a washer marker to dispense one washer marker at a time when placing the rod against the planar surface and by exerting downward pressure on the washer markers on the rod, and the other end of said rod extending from the shoulder of its spring a distance substantially equal to a very small fraction of the thickness of a washer marker to pick up the same one at a time from the planar surface by exerting downward pressure on the rod.

2. The hand dispenser of claim 1 characterized in that the length of said rod extending between the shoulders of said springs comprises a distance to hold sufficient washer markers on said rod to form a hand gripping surface comparable to a pencil to enable the operator to hold the washer markers to dispense and hold the rod to pick up one washer marker at a time from opposite ends of said rod.

3. The hand dispenser of claim 1 characterized by characters on said rod surface such as advertising to

increase the friction between the rod and said washer markers when held for dispensing.

4. The hand dispenser of claim 1, characterized by a loading tube having a bore at one end open and sufficiently large to receive the washer markers, a stop at the other end of said loading tube to prevent the washer markers from passing therethrough but open to receive said rod and spring shoulders, a loading box having an opening in one end to slidably receive the open end of said loading tube, and a stop adjacent said other end of said loading tube to limit the entry of said loading tube into said box, said loading tube being rotatable and reciprocal through said opening in said loading box to shuck and feed aligned washer markers into said open bore and to discharge a loaded rod inserted past said stop.

5. The hand dispenser of claim 4 characterized by an arcuate surface in said loading box aligned with said opening to receive said loading tube.

6. The hand dispenser of claim 4 characterized by a sleeve proportioned to receive said loading tube on the outer side of said loading box and forming said opening in said box to arrest said stop on said loading tube before the open end of said loading tube reaches the opposite end of said loading box.

7. The hand dispenser of claim 4 characterized in that said stop on said loading tube engages said box before the open end of said loading tube reaches the opposite end of said loading box.

8. The hand dispenser of claim 4 characterized by a lid on said loading box to retain the washer markers therein when said box is shaken.

9. The hand dispenser of claim 4 characterized in that said loading box and loading tube are transparent.

10. The hand dispenser of claim 4 characterized by a semi-cylindrical surface in said loading box and in alignment with said opening to receive said loading tube, and end box means to maintain uniform the exterior of said loading box for stacking.
